UNITED STATES PATENT OFFICE.

WILLIAM H. ROWE, OF LOS ANGELES, CALIFORNIA.

COIN-CONTROLLED MECHANISM.

Application filed March 21, 1927. Serial No. 176,848.

This invention relates to a coin freed mechanism for vending machines.

The general object of this invention is to provide an improved coin actuated plunger 5 for vending machines.

Another object of the invention is to provide a coin actuated plunger having a novel form of fraud prevention mechanism thereon.

10 Other objects and advantages of this invention will be apparent from the following description taken in connection with the accompanying drawings wherein:

Fig. 1 is a front view of a vending machine embodying the features of my invention.

Fig. 2 is a section through the cabinet taken on line 2—2 of Fig. 1 showing one of my improved coin actuated plungers.

Fig. 3 is a section on line 3—3 of Fig. 1 20 with portions broken away to more clearly show the plunger mechanisms.

Fig. 4 is a fragmentary section through the cabinet showing a single plunger mechanism in elevation in a normal locked position, the plunger housing being in section.

Fig. 5 is a view similar to Fig. 4 showing the plunger unlocked by a coin and partly actuated.

Fig. 6 is a fragmentary section through 30 the cabinet showing a side elevation of one of the plungers in two positions: fully extended in the dotted line position and in a returning position in full lines.

Fig. 7 is a section of the plunger mechanism partly in elevation taken on line 7—7 of Fig. 4.

Fig. 8 is a top plan view, partly in section, of the plunger showing it moved to eject a package and to eject the coins into the coin 40 receptacle.

Fig. 9 is a view similar to Fig. 8 showing a perforated slug caught by one of the fraud prevention devices.

Fig. 10 is a fragmentary top plan view 45 partly in section of a single plunger showing a perforated slug being extracted by another fraud prevention device.

Fig. 11 is a section of the plunger mechanism taken on line 11—11 of Fig. 4.

50 Fig. 12 is a rear view of the plunger mechanism taken on line 12—12 of Fig. 4, and

Fig. 13 is a fragmentary bottom plan view 55 of the fraud prevention bell ringing mechanism, the bell, battery, and wiring being shown diagrammatically.

Referring to the drawings by reference characters I have shown a vending machine cabinet at 10 embodying the features of my invention. This cabinet includes L-shaped side members 11 joined at the rear by a back 60 12 and in the front by a plate 13 and an angular bar 14. Above the plate 13 the cabinet is provided with a shelf 15 which has a plurality of coin slots 16 therein. Above the shelf 15 there is a door 17 hinged as at 18 to one of the sides 11 and provided with locking means 19 at the other side of the cabinet.

65 The closure 17 allows access to the storage compartments 20 in which the packages to be vended, shown as packages of cigarettes 21, 70 are arranged. The compartments are defined by partitions 22 which have horizontal base flanges 23 extending part of the length thereof. These base flanges serve as supports for the cigarette packages. Although 75 in the following specification I refer to my invention as used for vending cigarettes it will be understood that the invention may be used for other purposes or for vending other articles.

80 Arranged below the shelf 15 I provide a coin receptacle 25 secured to each of the sides 11. The bottom of the coin receptacle is closed by a trap door 26 which is hinged at the rear thereof at 27 and provided on its front 85 edge with an extending tongue 28. The door 26 is adapted to be normally held in a closed position by a spring 29.

85 To allow of the removal of the contents of the coin receptacle 25 I provide in the front plate 13 a removable closure 30 adapted to be locked in position by a lock 31 and adapted to hold the trap door 26 in a closed position when in place by retaining the tongue 28 of the door between the lower edge of the lock 31 and a rearwardly extending lug 32 formed on the rear of the closure 30.

90 The coin actuated plungers for ejecting the packages of cigarettes 21 are indicated generally at 35. These plungers have cylindrical end portions 36 which pass through apertures 37 in the front plate 13. The plungers are provided with rectangular portions 38 which are notched as at 39. Each plunger is mounted in a case 40 which has flanges 41 thereon shown as removably engaging undercut notches on lugs 42 arranged on the underside of the shelf 15. Lugs 43 on the rear face of the front plate 13 serves to position the case 40. Each case 40 is adapted to be supported 100 105 110

by engaging the bottom of a recess 44 formed in the side walls of the coin receptacle 25. The recesses 44 are arranged in opposed pairs with one pair for each case 40.

5 The shoulder 47 on the plunger is adapted to engage the end faces 48 of a pair of independent dogs 49 which are pivoted at 50 to the case 40. The construction is such that normally the plunger has but little movement 10 on account of its engagement with the faces 48 of the dogs 49.

Each plunger adjacent the shoulder 47 is provided on each side face with a notch 51 which in conjunction with the adjacent wall 15 of the casing 40 forms a coin slot. Each coin slot is normally disposed directly below one or a pair of slots 52 in the end 53 of the casing. Each slot 52 in the casing is disposed directly beneath a coin slot 16 in the shelf 15.

20 My improved coin actuated plungers are particularly applicable for use where it is necessary to insert two coins which may be of different value in order to effect operation of the machine, and the sizes of the slots 16 and 25 52 and the notch 51 will be determined by the size of the coin required to operate the machine.

Each of the dogs 49 is provided with a cut-away portion 54 which has an inclined lower 30 surface 55. When the proper coin is inserted in each slot and the plunger 35 is pressed inwardly the coins will engage and ride up the surfaces 55 and rock the dogs 49 upwardly as the plunger moves in so that the end face 48 35 will clear the shoulder 47 whereby the plunger may advance (see Fig. 5).

The locking dogs 49 are also provided with outwardly and rearwardly inclined lugs 56. As the coin advances rearwardly from the position shown in Fig. 5 it will pass the inclined 40 surface 55 and allow the dogs 49 to swing downwardly on its pivot until the inclined lug 56 engages the coin. As the plunger moves rearwardly the coins ride up the lugs 45 56 and are forced out of the notches or slots 51.

The case 40 is provided with an aperture 58 in each side and through these apertures the coins are discharged into the coin receptacle 25. In Fig. 8 at 59 I show coins which are 50 being ejected from the plunger mechanism into the coin receptacle 25. The pivoted dogs 49 are each adapted to be normally retained in contact with the upper face of the plunger by flat spring members 60.

55 At the rear end of each plunger I provide a pawl 61 (see Fig. 12) pivoted at 62 to a reduced lip 63 formed on the plunger bar 38. This pawl 61 is provided with a slot 64 for mounting it on the lip 63 and is so pivoted to 60 the lip that it normally assumes a vertical position so that when the plunger is moved rearwardly as shown in Fig. 5 the tip 65 of the pawl will engage the lowermost package of a compartment and push it off of the flanges 23.

65 On a return of the plunger the pawl is adapt-

ed to assume an inclined position and ride under the new lowermost package as clearly shown in Fig. 6.

The plunger mechanism is normally adapted to assume a locked position as shown in Fig. 4 by providing a coiled spring 66 which is secured at one end to a downwardly extending lug 67 on the plunger bar 38, and anchored to another downwardly extending lug 68 on the case 40. The spring 66 passes through a slot 68' in the rear wall of the coin receptacle 25 while the lug 68 is positioned in a slot 68''. The slots 68' and 68'' are merely notches in the bottom wall of the recesses 44.

To prevent surreptitious use and particularly for extracting apertured slugs from the plunger mechanism I provide a device consisting of dogs 70 pivoted at 71 to lugs 72 on each side of the casing 40 as clearly shown in Fig. 11. Each dog 70 includes a curved spur 73 adapted to normally rest against the back wall of a slot 74 provided in the bar 38. When an apertured slug as shown at 75 in Fig. 10 is inserted in a coin slot and the plunger is moved rearwardly the point of the spur will 90 pass into the aperture in the slug and on a further rearward movement of the plunger mechanism the point of the spur will be raised by the inclined portion 75' of the plunger and the coin will be forced out of the notch 51 of the plunger, thus preventing the slug from actuating one of the dogs 49. As the plunger mechanism is released and moved forward the rear wall of notch 51 will strike the slug causing the pivoted dog 70 to swing outwardly 95 and thus due to the curved formation of the spur 73 the slug will be swung outwardly and allowed to drop free of the plunger mechanism.

To further prevent apertured slugs from 105 actuating the plunger mechanism, if they should for any reason happen to pass by the dogs 70 I may provide an additional safety device mounted on either side of the case 40 and indicated generally at 77. A single device 77 consists of a bolt 78 mounted in an aperture of a downwardly extending tongue 79 integral with the case 40 and in an aperture 80 in the side wall of the case. The bolt 78 has a washer 81 secured thereto and is adapted to be normally pressed inwardly by a coil spring 82 interposed between the washer and the tongue 79. A coin will force the bolt 78 outward and will glide under the bolt 78 but when an apertured slug is used the bolt 78 will move into the aperture of the slug and prevent any further movement as shown in Fig. 9. I preferably round off the rear side of the inner end of the bolt 78 as at 84 so that the slug may move forward again with the plunger mechanism to give the dog 70 another chance to extract the slug from the plunger mechanism.

I also prefer to provide an audible signal which will give a warning when an apertured 130

slug is being used. This device includes a pair of contacts 85 and 86 on the under side of the shelf 15 adjacent to the rear end of each of the plunger mechanisms. The contacts 85 and 86 are mounted on an insulated block 87 which is secured to the shelf 15 by screws 88 and the contacts 85 are all connected together as by a bar 89 and all of the contacts 86 are similarly connected by a bar 90 (see Fig. 13). The bar 90 is connected to a bell 91 by a wire 92 and the bar 89 is connected to the bell by a wire 93 through a battery or other source of power 94.

For forming contact between a set of contacts 85 and 86 I provide a contact bar 95 mounted in and adjacent the end of the plunger bar 38 and insulated therefrom. When the plunger mechanism is stopped by the safety device 77 as shown in Fig. 9 the contact bar 95 will bridge the contacts 85 and 86 and cause the bell 91 to actuate. When the plunger mechanism is actuated properly by coins of the right denomination there will be only a momentary jingle of the bell 91.

From the foregoing description it will be apparent that I have invented a coin actuated mechanism which is highly efficient and which can be economically manufactured and that my mechanism is provided with novel means for preventing fraudulent use of the mechanism.

What I claim is:

1. In combination with a vending machine including a cabinet, a coin actuated mechanism comprising a casing, a plunger in said casing, means to prevent actuation of said plunger said means including a coin freed member, means whereby insertion of an apertured slug will prevent movement of the plunger, means for sounding an alarm when said plunger is operated after insertion of an apertured slug said alarm sounding means comprising a transverse bar mounted on and insulated from said plunger, and a pair of contacts insulated from one another and mounted on and insulated from said cabinet, one of said contacts being electrically connected to an alarm means, and the other of said contacts being electrically connected to said alarm through a source of electric energy.

2. A coin actuated plunger comprising a housing, a plunger in said housing, a coin slot in said housing and a coin slot in the side of said plunger and a fraud prevention device comprising a dog pivoted to said housing, said dog having a spur thereon, said spur being adapted to enter the aperture of an apertured slug in said coin slot of said plunger when said plunger is actuated and remove said slug from said coin slot upon actuation of said plunger.

3. A coin actuated plunger comprising a housing, a plunger in said housing, a coin slot in said housing and a coin slot in the side of said plunger, a fraud prevention de-

vice comprising a dog pivoted at its upper end to said housing, said dog having a spur thereon, said spur being curved forwardly and having its free end pointed, said dog being normally adapted to hang in a vertical position so that the pointed end of said spur abuts the side of said plunger, said spur being adapted to enter the aperture of an apertured slug in said coin slot of said plunger when said plunger is actuated thereby causing the slug to ride upon the curved spur and be removed from said coin slot of said plunger, said dog being adapted to swing upon its pivot to allow said slug to drop from said spur.

4. In a device of the class described a coin actuated plunger including a housing, a plunger in said housing, a coin slot in said housing and a coin slot in the side of said plunger, a fraud prevention device comprising a pivoted dog, said dog having a spur thereon, said spur being curved forwardly and having its free end pointed, said dog being normally adapted to hang in a vertical position so that the pointed end of said spur abuts the side of said plunger, said spur being adapted to enter the aperture of an apertured slug in the coin slot of said plunger when said plunger is actuated, thereby causing the slug to ride upon the curved spur and be removed from said coin slot of said plunger, said dog being adapted to swing upon its pivot to allow said slug to drop from said spur, catching means associated with said housing whereby an apertured slug passing said fraud prevention device will coact with said catching means to prevent further rearward movement of said plunger, said catching means comprising a spring pressed member, said member being adapted to enter the aperture of an apertured slug in said coin slot of said plunger whereby the rearward movement of said plunger will be arrested, means on said member to free said apertured slug from said plunger upon a forward movement of said plunger so that said plunger may be moved to a position where said previously mentioned dog may again act to remove said slug from said coin slot of said plunger.

5. A coin actuated plunger comprising a housing, a plunger in said housing, a coin slot in said housing and a coin slot in the side of said plunger, fraud prevention means associated with said plunger and operable to extract an apertured slug from said plunger coin slot upon actuation of said plunger, other fraud prevention means associated with said housing whereby an apertured slug unextracted from said plunger by said first fraud prevention means will coact with said second fraud prevention means to prevent full rearward movement of said plunger.

In testimony whereof, I hereunto affix my signature.

WILLIAM H. ROWE.
